R. W. ERDLE.
STENCILING DEVICE.
APPLICATION FILED APR. 19, 1921.

1,419,663.

Patented June 13, 1922.

Attorneys.

UNITED STATES PATENT OFFICE.

REINER W. ERDLE, OF NEW YORK, N. Y., ASSIGNOR TO RADIUM DIAL COMPANY, OF PITTSBURGH, PENNSYLVANIA.

STENCILING DEVICE.

1,419,663.

Specification of Letters Patent. Patented June 13, 1922.

Application filed April 19, 1921. Serial No. 462,688.

To all whom it may concern:

Be it known that I, REINER W. ERDLE, a citizen of Germany, and a resident of New York, in the county of New York and State 5 of New York, have invented certain new and useful Improvements in Stenciling Devices; and I do hereby declare the following to be a full, clear, and exact description of the invention, such as will enable others 10 skilled in the art to which it appertains to make and use the same.

This invention relates to stenciling devices and more particularly to means for facilitating the application of luminous material 15 to characters on dials and other devices,— one object of the invention being to provide means whereby the dial or other device may be accurately positioned and held with respect to the stencil, and also to provide simple means to hold the stencil and to permit 20 the same to be moved toward and from the dial or other object on which the luminous material is stenciled.

With this and other objects in view, the 25 invention consists in certain novel features of construction and combinations of parts as hereinafter set forth and pointed out in the claims.

In the accompanying drawings, Figure 1 30 is a view in elevation illustrating my improvements, and Figure 2 is a plan view.

1 represents a frame or support which may have general triangular shape and from the apex of this frame, an arm 2 projects in an 35 inclined direction for a purpose hereinafter explained. One face of the triangular frame 1 affords an inclined platform 3 on which the base 4 of a guide 5 is mounted and may be adjustably secured to said platform with 40 the use of one or more bolts such as indicated at 6. A carriage 7 is mounted on the guide 5 and is horizontally adjustable thereon by means of a screw feed, such as indicated at 8, and the screw of this feed may be provided 45 with a hand wheel 9 having a suitable knob 10 thereon. The carriage 7 is provided with guides 11 disposed at right angles to the guide or guides 5, and mounted to slide on said guides 11 is a carriage 12 and for moving 50 this carriage in a direction at right angles to the direction of movement of the carriage 7, a screw feed indicated at 13 may be employed,—the screw of said feed having thereon a wheel 14 provided with a knob 55 or handle 15. The carriage 12 carries a

plate or bracket 16 which is suitably secured thereto and on this plate or bracket, a worm wheel 17 is mounted, a worm 18 being provided for actuating said worm wheel and the shaft which carries the worm 18 may be provided with a knob 19 to facilitate its manual operation.

A platform or table 20 is supported, through the medium of standards 21, by the worm wheel 17, and the table 20 is provided 65 with a facing of rubber or similar material, as indicated at 22.

A plurality of pipes 23 (two such pipes being shown in the drawing) pass through holes in the table 20 and communicate with small holes in the rubber facing 22, as indicated at 24. The pipes 23 are connected with a coupling 25 and with the latter a pipe 26 communicates at one end and the other end of this pipe is provided with a rubber bulb 75 27. These devices provide pneumatic or suction means for holding a dial 28 to be operated upon, tightly against the rubber facing of the table 20.

The stencil 29, through the medium of 80 which luminous material may be applied to the characters on the dial 28, is supported by a frame 30 having hinged connection, as indicated at 31 with a bracket 32, and the latter is provided with arms such as indicated at 33 which lie against the inclined arm 2 of the frame 1. The arms 33 are provided with elongated slots 34 for the passage of bolts 35, said bolts also passing through the arm 2 and provided with 85 threaded portions to receive thumb nuts 36 whereby the bracket 32 carrying the stencil frame is adjustably secured to the arm 2 of the supporting-frame 1.

The stencil 29 may be made of sheet celluloid and is clamped at one edge between plates 37 by means of bolts 38 provided with thumb nuts 39. The other or lower edge of the stencil 29 is clamped, by means of bolts 39 and nuts 40, between plates or strips 41 100 and 42. The plate or strip 42 is provided at its respective ends with rods 43 which pass through guides 44 rigid with the open frame 30, and on said rods, springs 45 are located between the guides 44 and the bar 42. It 105 will be observed that the thin stencil sheet is fixed at one end to the stencil frame 30 and that the other end of said stencil sheet is so connected with the frame 30 through the medium of the spring pressed clamping 110

strips that said stencil sheet will be held taut so that it may lie flat against the dial or other object to be stenciled.

The object to be stenciled with luminous material, (a clock-dial for example) is placed on the rubber faced table 20 and held thereon by suction, as previously explained. The hinged stencil carrying frame 30 may now be brought down over the table 20 and then the frame 30 and the stencil carried thereby, will be lowered by lowering the bracket 32 to which the frame 30 is hinged, thus bringing the stencil 29 into close contact with the dial. The operator will now manipulate the various adjusting devices hereinbefore described until the characters on the dial shall accurately align with the characters of the stencil. The luminous material may now be applied through the stencil characters onto the dial characters after the manner usually employed in stenciling operations.

By means of my improvements luminous material may be very quickly and accurately applied to characters on such objects as clock dials and the like and the loss of the expensive luminous material and the inaccurate application of the same as well as the time consumed incident to the hand work heretofore employed, will be obviated.

Having fully described my invention what I claim as new and desire to secure by Letters-Patent, is:

1. In a stenciling device, the combination with a work supporting table and means for rotatably and laterally adjusting the same, of means for retaining work on said table, a stencil frame and means adjustably supporting said stencil frame whereby the stencil may be moved toward or away from the work while in a plane substantially parallel with that of the work.

2. In a device of the character described, the combination with a work supporting table and means for adjusting the same, of suction devices for holding work in position

on said table, a stencil frame, a stencil carried thereby, and means for adjustably supporting said frame whereby the stencil may be moved relatively to the work on said table.

3. In a device of the character described, the combination with a worm wheel and means for turning the same, of a table supported by said worm wheel and provided with a yielding facing, means operable to hold the work against said yielding facing, means for adjusting the worm wheel and table carried thereby in directions at right angles to each other, a stencil frame, and a stencil carried by said frame over said table.

4. In a device of the character described, the combination with a work table and means for adjustably supporting the same, of a yielding facing on said table and having a plurality of holes, pipes passing through the table and communicating with the holes in said yielding facing, a bulb connected with said pipes, a stencil, and means for supporting the stencil over the work held on the yielding facing of said table.

5. In a device of the character described, the combination with a frame having an inclined platform and provided with an inclined arm, of a work supporting table, supporting and adjusting means between said table and said platform, a bracket adjustably secured to the inclined arm of said frame, a stencil frame hinged to said bracket, a stencil secured at one end to said stencil frame, bars between which the other end of the stencil is clamped, and yielding means connecting said bars with the stencil frame.

In testimony whereof, I have signed this specification in the presence of two subscribing witnesses.

REINER W. ERDLE.
